JOSEPH S. PECKER, OF PHILADELPHIA, PENNSYLVANIA, ASSIGNOR TO PATENT DEVELOPMENT CO., A CORPORATION OF PENNSYLVANIA

MACHINE FOR REPAIRING KNITTED FABRICS

Application filed June 12, 1928. Serial No. 370,313.

The invention relates to machines for repairing knitted fabrics.

The object of the present invention is to provide a simple, practical and comparatively inexpensive machine, of strong and durable construction, designed for repairing runs in stockings and capable of operating on stockings either from the toe towards the hem or from the hem towards the toe. This feature is material and essential, due to the fact that in order to make a correct repair the reknitting of the lost stitch must conform to the original knitting in order that the repaired hose may present the same appearance after repair as originally, and although this is possible with the usual hand method of placing the ladder-like threads of a run over a cup, heretofore nothing has been developed to repair a stocking in either direction with a mechanically actuated needle.

A further object of the invention is to provide a means for repairing runs of more than a single width. This is important in as much as runs develop two or three widths extending parallel to each other, and in the repair of such runs it is preferable to maintain the material in a taut condition and in a position unchanged with respect to the supporting means after one run has been repaired and while a second run and a third run are likewise repaired.

A further object of the invention is to render it possible to repair a run of substantially the full length of the hose or for a length equalling that of the average run without having recourse to shifting on the supporting means the material in which the repair is to be made, as is necessary by the present hand method as well as machine method where only a small portion of the run to be repaired can be presented at a time to the needle.

A further object of the invention is to provide means for changing the position of the mechanically actuated needle from a vertical position to a slightly inclined or angular position. This becomes necessary in order to make the machine adaptable to the use of various styles of needles, particularly those which have so-called side guards to protect

the latches and which, in order to function properly, must be inserted in the cloth at a slight angle to the vertical.

A further object of the invention is to provide means for adjusting the stroke of the needle without recourse to the removal and changing of parts, but by a simple method of turning a screw accessible from the exterior of the machine. The adjustment of the stroke is also essential to the use of various styles of needles, as varying the length of the latches, or the hooks or the guards requires corresponding changes in the stroke of the needle.

A further object of the invention is to provide a hollow mandrel over which the material to be repaired can be placed, having a slot at the point of re-knitting adapted to permit the needle to pick up the lost stitches and at the same time enable rays of light from interiorly arranged illuminating means to be projected through the slot so that the operator can readily see the ladder-like runs and may accurately operate on the same with greater speed than is possible where the stitches of the fabric to be repaired cannot be clearly discerned.

Another object of the invention is to provide a means of illumination which will not be in the direct line of vision of the operator of the machine and in which the film of an electric lamp will be entirely out of the direct vision of the operator and beyond the hollow form, thereby producing the double advantage of eliminating the glare and preventing the heat of the light from heating the form which supports the material to be repaired.

Another object of the invention is to provide means for holding the material to be repaired taut over the hollow form or mandrel both laterally and longitudinally of the same, and to enable the clamping or holding means to be shifted out of the path of the needle without changing the position of the fabric.

Another object of the invention is to provide in a machine in which the needle is movable along the run to be repaired, a collapsible means for supporting the needle and encasing and housing the needle driving means,

to permit the shifting of the needle in the direction of the run of the material by the operator without the necessity of extending the supporting means rearwardly through the main frame to the other side of the driving wheel, thereby providing a compact construction.

A further object of the invention is to provide a driving means for the needle which will be arranged interiorly of the needle supporting means and at the same time be collapsible in the same manner as the outer casting or support.

Another object of the invention is to provide between a needle carrying plunger and the positive action of the needle driving means, a yieldable connection adapted, in case some foreign object is placed between the hollow form or mandrel and the needle, to yield and thereby prevent injury to either the needle or the object, and also to provide a means of voluntarily stopping the operating of the needle by the operator while the machine is in action.

Another object of the invention is to provide a means for quickly reversing the position of the needle so that a run can be repaired by operating on the same either from the toe towards the hem or from the hem down towards the toe.

A further object of the invention is to provide a form or mandrel that will permit the stitching of a stocking over the form substantially the full length of the stocking and to provide a narrow portion on the form adapted to fit in the narrow part of the stocking near the toe, thus permitting the repair of a run close to the toe and at the same time providing a form or a mandrel which may be used as a means of inspecting a stocking for runs.

With these and other objects in view, the invention consists in the construction and novel combination and arrangement of parts hereinafter fully described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a side elevation of a stocking repairing machine constructed in accordance with this invention.

Fig. 2 is a plan view of the same.

Fig. 3 is a central longitudinal sectional view of the stocking repairing machine.

Fig. 4 is a horizontal sectional view on the line 4-4 of Fig. 1.

Fig. 5 is a front elevation partly in section.

Fig. 6 is a transverse sectional view taken substantially on the line 6-6 of Fig. 1.

Fig. 7 is a side elevation of a portion of the frame and hollow form or mandrel.

Fig. 8 is a detailed transverse sectional view through the rear portion of the frame illustrating the construction of the means for guiding the hollow form or mandrel in its lateral adjustment.

Fig. 9 is a plan view of the hollow form or mandrel, the non-metallic plates or strips being partly broken away to illustrate the recess in which the plates or strips are seated.

Fig. 10 is a longitudinal sectional view of the collapsible driving shaft for actuating the reciprocating needle.

Fig. 11 is an enlarged vertical sectional view illustrating the construction of the needle supporting and actuating means.

Fig. 12 is a transverse sectional view of the same.

Fig. 13 is a detail sectional view of the lower nut of the tubular plunger section.

Fig. 14 is a detail sectional view of the needle holding clutch or collet.

Fig. 15 is a reverse plan view of the lower nut of the tubular section of the plunger.

Fig. 16 is a reverse plan view of the needle holding clutch or collar.

Fig. 17 is a detail perspective view of the adjustable slide which carries the eccentric needle driving pin.

Fig. 18 is a detail sectional view on the line 18-18 of Fig. 11.

Fig. 19 is a detail sectional view on the line 19-19 of Fig. 11.

Fig. 20 is a detail perspective view of one of the clips for clamping a stocking on the hollow form or mandrel.

In the accompanying drawings, in which is illustrated the preferred embodiment of the invention, the stocking repairing machine comprises in its construction a main frame 1 preferably consisting of a hollow casting which is in the form of a vertical standard or support provided at the bottom with an enlarged base 2 designed to be secured upon a table 3 or other suitable supporting surface.

The vertical body portion of the support has a gentle taper and is provided at the top with a horizontal tubular bearing portion 3a in which is mounted a collapsible telescoping driving shaft 4 and a collapsible telescoping support 5, constituting a hollow arm or casting for housing the telescoping driving shaft, the collapsing or telescoping of the hollow support or arm and the driving shaft permitting a needle 6 to be moved longitudinally of a hollow stocking supporting form or mandrel 7 for looping the ladder-like threads of a run for repairing the same in a manner similar to the hand operation of a needle, as is well known in the art.

The hollow form or mandrel 7 is arranged horizontally and is secured at its inner or rear end to the main frame intermediate of the ends of the upright portion thereof and

110

115

120

125

130

is provided with a tapered outer or front end 8 adapted to be inserted in the narrow portion or toe of a stocking 9 for enabling runs to be repaired which extend to the toe portion of the stocking. The inner or rear end portion 10 of the stocking supporting form is preferably rectangular in cross section, as clearly illustrated in Fig. 6 of the drawing, to provide parallel horizontal upper and lower faces 11, which fit between and are guided by upper and lower horizontally guided faces 12 and 13 of the main frame. The main frame is provided at the front with an opening 14 into which the rear end of the form 10 extends, and the upper guiding face 12 is formed by the top wall of the opening 14, while the lower guide is formed by a cross bar 15, preferably formed integral with the main frame and connecting and bracing the sides thereof.

The main frame 1 is also provided at the top of the opening 14 with a rear wall 16 which presents a front vertical face to the rear end of the hollow form and cooperates with the upper and lower faces 12 and 13 in the guiding of the form when the same is moved laterally to change it from a central position with respect to the needle to a position at either side thereof to cooperate with the lateral adjustment of the needle herein-after explained, for the purpose of adapting the machine for different types of needles. The vertical abutting face of the rear wall 16 forms a stop for the hollow form, and the latter is actuated in its lateral adjustment by a transversely disposed shaft 17 provided with screw threads 18 which engage a threaded opening 19 in a bracket 20 which is secured to the lower face of the hollow form 7 adjacent the rear end thereof, as clearly illustrated in Fig. 3 of the drawings. The bracket 20 fits against the lower face of the rear substantially rectangular portion of the hollow form, and is fastened to the same by screws 21 or other suitable fastening devices. The shaft 17 is mounted in suitable bearings 22 and 23 in the sides of the main frame and it is held against longitudinal movement therein by means of a set collar 24 at one end of the shaft 17, and a lever 25 mounted on the other end of the shaft. The set collar and the lever may be secured to the shaft by any suitable fastening means, and the lever, which has an upwardly extending operating arm, also has a short depending arm 26, which carries an automatically operating locking plunger 27 forming a catch and adapted to engage any one of an arcuate series of pockets or sockets 28, preferably consisting of concavities arranged at suitable intervals and adapted to receive the engaging end 29 of the plunger, which is preferably rounded to fit the concavities 28. The plunger 27, which is also provided with an annular flange 30, is maintained in contact with

the adjacent portion of the frame 1 by a coiled spring 31 which is supported within a cylindrical casing 32 preferably formed integral with and carried by the arm 26. The annular flange of the plunger fits within the cylindrical casing and is located intermediate of the ends of the plunger, which also extends into the coiled spring 31, as clearly illustrated in Fig. 6 of the drawings.

The cylindrical casing 32 is closed at its outer end and is provided with an open inner end, and when pressure is exerted on the operating arm of the lever 17 to partially rotate the shaft, the plunger will be forced out of the engaged pocket and will permit the shaft to be rotated for sliding the hollow arm laterally in either direction to and from a central position. The pockets 28 are formed in an enlargement 33 of the main frame, which enlargement presents a flat vertical outer surface in which are formed the pockets 28. The hollow form is adapted to be moved to either side of the central position illustrated in Figs. 5 and 6 of the drawings, and the space between the sides of the frame and the sides of the hollow form in practice will be ample to permit the desired lateral adjustment of the hollow form.

When the hollow form is adjusted laterally to a position at either side of the center, the needle will be shifted laterally by swinging it to one side or the other as hereinafter fully explained, and the adjustment of the form will correspond with the adjustment of the needle and will permit the needle to operate in the inclined position necessitated by the particular construction of certain needles employed for repairing knitted fabrics. The swinging of the operating arm forwardly or rearwardly will rotate the threaded shaft and slide the hollow arm in the guides of the frame and the locking devices carried by the operating lever will automatically retain the shaft in its adjusted position.

The hollow form is rounded transversely at opposite sides of the upper portion at 34 and is also rounded at the bottom and the front portion is tapered preferably by curving the bottom portion upward at 35 and forming a rounded nose as shown. The front end is rounded both horizontally and vertically, and the narrow reduced front portion of the hollow form is adapted to fit within the narrow or toe portion of a stocking to enable a run to be repaired in such ordinarily more or less inaccessible portion, which is difficult to repair by hand and practically impossible with machines not provided with means for supporting the narrow or toe portion of a hose. The rounding of the side portions of the hollow form at the top thereof provides bulging side portions adapted to be engaged by spring clips 37 of approximately U-shape extending across the hollow top of the form and engaging the fabric of the hose at the

top and sides thereof and capable of maintaining the fabric taut with the cross threads of a run in proper position to be operated on by the needle.

5 The spring clips 37, which are designed to be constructed of spring steel or other suitable material, are slideable longitudinally of the form to enable them to be adjusted to the proper or desired position for holding the fabric and to arrange them out of the path of the needle, and any desired number of spring clips may, of course, be employed. The approximately U-shaped clip 37 has a straight top portion and curved sides which 10 conform to the configuration of the rounded laterally bulged side portions of the hollow form. The terminals of the spring clip are 15 preferably coiled as shown to avoid presenting any sharp edges to the stocking and at the same time permit their manipulation by the 20 operator.

The hollow form is provided at its rear end at the top with spaced upwardly projecting bearing lugs 38 in which is journaled a transverse shaft 39 having fixed to its inner end portion a clamping arm 40 located between the bearing lugs and extending forwardly therefrom over the rear portion of the hollow arm and provided at its outer or front 30 end with a laterally extending jaw 41 provided at its lower face with a yieldable covering 42 preferably consisting of a piece of rubber or other suitable material and forming a lower fabric-engaging face for clamping the 35 stocking 43, as clearly illustrated in Fig. 3 of the drawings. The jaw of the clamping arm in gripping the stocking cooperates with non-metallic strips 44 of rubber or other suitable material, seated in a recess 45 in the upper 40 face of the hollow form and extending the entire length of the needle-receiving slot 46 at opposite sides thereof.

The slot 46, which extends substantially the entire length of the hollow form, permits the 45 needle 6 to reciprocate through the hollow form for manipulating the cross threads of a broken run in the ordinary manner to repair the run. The hollow form is designed to be of sufficient length to extend approximately 50 the full length of the leg portion of a stocking to enable runs of the usual length to be repaired without necessitating the changing of the position of the stocking on the supporting form, but the latter may, of course, be 55 of any desired length, as will be readily understood. The clips 37 cooperate with the non-metallic strips 44, and while two are illustrated in Figs. 1 to 3, inclusive, of the drawings, the number may be varied, and in practice the clips will be arranged in advance and in rear of the needle when the latter is placed in working position, so that the fabric will be firmly held on the form under the desired tension to enable the operator to move or 60 adjust the mechanically actuated needle along

the run from one cross thread to another in repairing a stocking.

The clamping arm 40 may be keyed or otherwise secured to the shaft 39, which extends laterally from one side of the frame of 70 the machine and has secured to it a rearwardly extending operating arm 47. The operating arm 47, the shaft 39 and the clamping arm 40, which are rigid with one another, constitute a clamping lever for holding the 75 stocking near the hem, and the said operating arm, which preferably extends rearwardly beyond the upright portion of the clamping frame, is designed to be connected with a foot treadle by a rod 48 provided at its upper end with an eye 49 which is linked into an eye or opening 50 in the rear end of the operating arm 47.

A coiled spring 51, which extends upwardly from the rear end of the operating arm 47, 80 is linked into the eye 50 thereof and also into an eye 53 mounted on the frame 1 beneath the top bearing portion thereof, but the coiled spring, which yieldably maintains the clamping lever in engagement with the 85 stocking, may be mounted in any other desired manner, and both the spring 51 and the rod 48 provide a flexible connection at their point of attachment to the operating arm 47 and do not interfere with the limited lateral 90 adjustment of the hollow form. When the foot treadle is depressed the clamping lever will be lifted out of engagement with the stocking on the hollow form or elevated to a position which will permit the stocking to be 95 placed on the form or to be adjusted as required, and when the foot pedal is released the spring will operate to swing the clamping arm 40 downward into engagement with the fabric or form and will yieldably maintain 100 the clamping arm in such engagement. A 105 spring of any desired strength may be employed, and if desired any suitable tensioning means may be provided for varying the clamping action.

110 In order to enable the operator to see clearly the cross threads of a run in a stocking or other fabric, so that the latter may be repaired with accuracy and speed, the machine is equipped with interiorly arranged illuminating means preferably consisting of an electric lamp 54 mounted in a socket 55 which is supported upon cross pieces 56 of the main frame, but any other suitable form of support may, of course, be employed. The electric 115 light socket 55 will in practice be arranged in a suitable lighting circuit and will be controlled in the ordinary manner by a suitable switch, to enable the electric lamp to be lighted and extinguished as required. The 120 electric lamp, which is located in the hollow upright or standard portion of the main frame, extends from the supporting means at the base thereof to a point in line with the 125 top of the hollow arm and the socket is 130

equipped with a main reflector 57 and an auxiliary reflector 58. The main reflector, which is mounted upon the electric lamp in any desired manner, is located at the back 5 of the lamp and conforms to the configuration of the same, and covers substantially one-half of the electric lamp. The auxiliary reflector, which is arranged in front of the electric lamp, is preferably concavo-convex, as 10 shown, and is secured to the front end of a curved supporting arm 59, and is interposed between the lamp and the open rear end of the hollow form so as to prevent direct rays of light striking the eye of the operator. The auxiliary reflector 58 is interposed between 15 the eye of the operator and the lamp, so that the light is not in the direct line of vision of the operator and the latter will not be affected by the glare of the light. The auxiliary reflector is adapted to throw the 20 rays of light from the front of the lamp to the main reflector at the back thereof, and the latter will diffuse the light through the hollow form and illuminate the latter sufficiently 25 to enable the threads of fabric to be clearly seen by the operator. In practice, the interior of the hollow form will be polished, painted, or otherwise treated to produce an 30 interior surface having good reflecting characteristics, and by the indirect lighting of the interior of the hollow form a soft diffused light will be provided which will bring out the cross threads more clearly than if a 35 strong bright light were projected through the longitudinal needle-receiving slot of the hollow form. As the cross threads of a run are fairly close together, they will be clearly defined. As the operator must gauge the 40 shifting of the needle and move the same a definite distance controlled by the distance between the cross threads, it will be apparent that a considerable strain is placed upon the operator in judging the spacing of the needle 45 in timed relation with the spacing of the threads, and that the provision of a light to thus clearly bring out the threads will facilitate the operation of looping the run and increase production and at the same time lessen 50 the mental as well as the physical strain or fatigue of the operator.

The curved supporting member 59 extends over the top of the lamp 54 and is secured at its rear end to the top of the main reflector 55 and at its front end to the auxiliary reflector, as clearly illustrated in Fig. 3 of the drawings. The auxiliary reflector forms a combined reflector and shield for protecting the eyes of the operator and for reflecting rays of 60 light to the main reflector. The upright portion or standard of the hollow main frame is provided at opposite sides with ventilating openings 60 located a short distance below the top of the frame and adapted to permit 65 the escape of heat from the lamp, so that the

fabric and the form will not be heated by the lamp.

The hollow telescoping extensible supporting arm 5 is composed of a plurality of sections 61 which are successively reduced from 70 the inner or rear end to the outer or front end of the hollow arm and are provided at the bottom with longitudinal slots 62 into which extend suitable projections or lugs 63 and 64 which limit the sliding movement of 75 the telescoping sections and prevent the same from being separated and at the same time prevent relative rotary movement of the tubular sections of the telescoping extensible supporting arm. The projections or lugs 63 are preferably formed by rivets, each being 80 mounted on the outer end portion of one of the telescoping sections and extending into the slot of the adjacent telescoping section. The other lug 64 is arranged at the inner or 85 rear end of the telescoping arm and is mounted on the main frame at the bottom of the tubular bearing portion 3 thereof and is in the form of a screw having a reduced portion extending into the slot 62 of the adjacent 90 section. The tubular bearing portion 3^a of the frame is provided with a lining sleeve 65 into which the rear section of the extensible arm telescopes. The tubular sections 61 of the extensible arm are adapted to slide on 95 each other to vary the length of the arm for moving the needle 6 longitudinally of the hollow form without the necessity of extending the supporting arm in rear of the main frame, as would be the case were the supporting arm made in a single piece and slidably mounted on the main frame to permit such adjustment of the needle. The screw which forms the lug 64 pierces the lining sleeve 65 and retains the latter in place within the tubular or sleeve portion 3 at the top of the 100 main frame.

The outer or front end of the extensible hollow arm carries a hollow head 66 of a substantially cylindrical form provided with 110 a reduced portion or neck 67 which fits within the front end of the hollow arm, as clearly illustrated in Fig. 11 of the drawings. The hollow head 66 abuts against the outer end of the extensible supporting arm and is secured to the same by a screw 68 which extends through a transverse slot 69 in the outer section of the extensible arm. The inner threaded portion of the screw pierces the reduced portion or neck 67 and extends into a bearing sleeve 70 arranged within the neck and fitted against a shoulder formed by a flange 71 of the terminal portion of the said neck. The transverse slot permits a partial 115 rotary adjustment of the hollow head to enable the needle 6 to be arranged either in a vertical position or in an inclined position at either side of the vertical, and the screw 120 68 will clamp the hollow head in its rotary 125 adjustment to maintain the needle in proper 130

position with relation to the needle receiving slot of the hollow form.

The shaft 4, which is housed within the hollow extensible arm 5 is composed of tubular telescoping sections 72 provided with longitudinal slots 73 arranged diametrically opposite each other and receiving transverse pins 74 which are mounted on the adjacent tubular sections and also on the front 10 end of a rear unslotted section 75 which is arranged within the tubular or sleeve portion of the frame, as clearly illustrated in Fig. 3 of the drawings. The transverse pins 74, which operate in the slots 73, limit the sliding movement of the tubular sections of the extensible drive shaft and prevent separation of the sections and at the same time enable the shaft to adjust itself with the adjustment of the hollow extensible arm 5 without projecting through the rear portion of the main frame. The hollow arm forms a casing or housing for the extensible driving shaft, and the rear section 75 thereof is arranged within a short sleeve 76 which is provided at its 20 front end with an annular flange 77, and which is keyed or otherwise secured at its rear end to the extensible shaft and a combined pulley and fly-wheel 78. The short sleeve 76 extends through a bearing collar 25 or ring 79 which is secured by screws or other suitable fastening devices to the main frame at the rear end of the tubular top portion 3 thereof. The bearing ring or collar 79 supports the rear end of the driving shaft, and 30 also has mounted on it a guard 80 which extends over the pulley portion 81 of the combined fly-wheel and pulley and prevents the operator when using the fly-wheel as a hand wheel, from coming in contact with a 35 driving belt 82. The pulley portion 81 of the combined hand wheel, fly wheel and pulley, is grooved to receive the belt 82 which extends downwardly to a grooved pulley 83 of a power shaft of a motor 84 suitably 40 secured to the main frame at the base thereof, but the motor may be mounted at any other desired point in any suitable manner, as will be readily understood. The motor is controlled in the usual manner, preferably 45 by foot operated rheostat, to secure the desired speed, so that the needle may be made to run either fast or slow, to meet the requirements of the operator. The guard 80 is substantially semi-circular, and is provided 50 at its inner edge with a centrally arranged substantially semi-circular flange 85, which is secured by screws or other suitable fastening devices to the upper portion of the bearing collar or ring 79, as clearly illustrated in 55 Fig. 5 of the drawings. The guard is provided at its outer edge with a substantially semi-circular flange 86 which extends over and houses the upper half of the pulley portion 81 of the combined fly-wheel and pulley. 60

65 The driving shaft is provided at its front

end with a fork 87 having a shank or stem 88 which is secured within the outer end of the extensible shaft by a pin 89 or other suitable fastening device. The stem 88 extends through the bearing sleeve 70, and a spacing 70 collar 90 is arranged on the stem and interposed between the bearing sleeve 70 and the outer end of the extensible shaft 4, as clearly illustrated in Fig. 11 of the drawings, the spacing collar 90 being secured to the shaft 75 by a key or pin or any other fastening means which pierces the collar and the stem. The collar is located within the annular flange 71 when the parts are assembled, and it provides a solid construction and a firm bearing or 80 abutment at the outer end of the extensible shaft.

The fork consists of spaced arms and a connecting portion, and the stem is arranged eccentrically of the connecting portion, being 85 located closer to one of the arms of the fork than to the other to increase the eccentric adjustment of a wrist pin 92 preferably formed integral with and carried by a slide- 90 able block 93 arranged between the arms of the fork and which is adjustable by means of a screw 94 to position the wrist pin the desired distance from the axis of the driving shaft. This enables the stroke of the eccentric drive of the shaft 4 to vary to adapt the machine to 95 different types of needles. The slideable block 93 is provided with a threaded opening 95 to receive the screw, which is mounted in suitable bearing openings of the arms of the fork. The screw is provided adjacent one end with 100 an annular groove 96 located within the opening of the adjacent arm of the fork and engaged by a pin 97 mounted on the fork at one of the arms thereof and extending across the bearing opening of the same at the inner 105 side thereof and operating in the annular groove of the screw. By this construction the screw is swiveled to the fork and is adapted to be rotated by a screw driver or other suitable tool for adjusting the slideable block 93. 110 The other end of the screw is provided with a groove 98 to receive the blade of a screw driver, and the hollow head 66 is provided at its top with an opening 99 to permit the introduction of a screw driver into the hollow 115 head so that the stroke of the needle may be adjusted without removing or changing any of the parts of the eccentric drive. The opening 99 is normally closed by a suitable cover 100 preferably pivoted to the head of a screw 101 or other suitable fastening devices and adapted to be swung to and from a position over the opening 99. The wrist pin 92 is arranged eccentrically of the slideable block 93 to cooperate with the eccentric arrangement 105 of the shank or stem of the fork and secure a maximum adjustment of stroke. The hollow head 66 is also provided with a removable face plate 102 to afford access to the interior 120 of the hollow head, and the latter has a de- 125

pending tubular extension 103 in which operates a yieldable needle-carrying mechanism adapted, as hereinafter described, to permit the needle to be held stationary by the operator without stopping the needle actuating mechanism and capable also of being stopped by an object interposed between the needle and the form without interference with the continuous operation of the needle actuating mechanism, so that the more perfect control of the machine in the operation thereof in repairing a knitted fabric may be had, and also to prevent injury to the operator or to the needle should the hand of the operator or other object be accidentally interposed between the needle and the form.

The wrist pin 92 receives the upper end of a pitman 104 secured on the wrist pin by a washer 105 and a key or pin 106, suitable bearing sleeves 107 being provided for the wrist pin and the pitman, as clearly shown in Fig. 11 of the drawings. The lower end of the pitman is bifurcated to receive the upper end of a vertically reciprocating plunger 108 which is connected with the pitman by a transverse pin 109, forming a pivotal connection between the lower end of the pitman and the plunger. The plunger 108, which is positively actuated, is yieldably connected with a tubular needle carrying plunger 110 by means of a head 111 and upper and lower coiled springs 112 and 113 located above and below the head 111 of the positively reciprocated plunger 108. The head 111 is secured to the positively actuated plunger 108 by a key or pin 114 and it carries a projection 115 operating within a longitudinal slot 116 in one side of the yieldably reciprocated plunger 110. The projection 115 preferably consists of a screw threaded into one side of the head 111, and the tubular plunger 110 operates within a fixed sleeve 117 secured in the lower portion of the depending tubular extension 103 of the hollow head by a set screw 118 mounted in a threaded perforation of the extension 103 and engaging a depression or concavity 119 formed in the upper portion of the guiding sleeve 117. The tubular extension 103 of the hollow head is counterbored at its lower portion to provide a shoulder 120 against which the upper end of the guiding sleeve 117 abuts.

The upper coiled spring 112 is interposed between the head 111 and an upper nut 122 having a central opening 123 for the plunger 108 and exteriorly threaded to screw into the upper end of the tubular plunger and flanged to form a shoulder for engaging the upper end of the said tubular plunger 110. The lower coiled spring 113 is interposed between the head 111 and a lower nut 124, which is exteriorly threaded to screw into the lower end of the tubular plunger 110 and held against rotary movement by means of a set screw 125 piercing the lower end of the tu-

bular member 110 and threaded into one side of the lower nut 124.

The lower nut is provided with a socket 126 extending downwardly from the upper end of the nut and terminating short of the lower face of the same and receiving a coiled spring 127 which is interposed between the bottom of the socket and a head 128 of an axially arranged pivot 129 extending through the bottom of the lower nut and into a socket 130 in a clutch section 131 secured to the pivot 129 by a transverse pin 132 or other suitable fastening device. The axial pivot is arranged in an opening 133 in the bottom of the lower nut, and the contiguous faces of the lower nut and the clutch member 131 are provided with coacting interlocking means for yieldably holding the clutch section 131 against rotation, and for permitting the clutch section 131 when the necessary force is applied, to be rotated one hundred and eighty degrees for reversing the needle 6 so that the hook may extend either forwardly or rearwardly, according to the direction in which it is desired to mend the run. The head 128 is secured to the axially disposed pivot 129 by a pin or key, and the cooperating interlocking means of the lower nut 124 constitutes a relatively fixed clutch section.

The clutch section 131 preferably consists of a diametrically disposed groove 134 formed in the lower face of the nut 124 and a diametrically disposed rib 135 formed integral with the rotary clutch member 131 and extending across the upper face thereof. The groove 134 and the rib 135 are triangular in cross section and are adapted to be readily engaged with and disengaged from each other by rotating the clutch section 131, the coiled spring 127 permitting longitudinal movement of the axially disposed pin in engaging and disengaging the said interlocking means. The rotary clutch section 131 is tapered below the upper end and is exteriorly threaded at 136 to receive a clamping nut 137 for causing the lower portion of the clutch member to grip the needle 6. The lower portion 138 of the clutch member 131 is split at right angles as shown in Fig. 16, and is provided with a needle socket 139, and the nut 137 is tapered at its lower portion at 140 both interiorly and exteriorly to engage the lower split tapered portion of the clutch section 131. By this construction the needle may be clamped to the adjustable clutch section 131 and needles may be readily removed and changed by loosening and tightening the clamping nut 137.

The guiding sleeve 117 is provided below the depending extension 103 with longitudinal slots 140 extending upwardly from the lower ends of the sleeve and terminating in enlargements or openings 141. The guiding sleeve is preferably split at four points at 140 and one of the slots is arranged in alignment

with the slot 116 of the tubular member 110, so that the enlargement at the upper end of such slot 140 will afford ready access to the screw 115.

5 The split lower portion of the guiding sleeve renders the guiding sleeve sufficiently resilient to enable the operator to compress the resilient portion and exert sufficient pressure on the yieldably mounted tubular member 110 to stop the needle without stopping the positively actuated plunger 108. The split portion of the guiding sleeve is knurled, checkered, or otherwise roughened exteriorly at 142 to enable it to be positively held by 10 the operator without danger, so that the needle may be accurately manipulated by the operator. The needle 6 is provided at its lower end with a hook 143 and it has a pivoted latch 144 and is adapted to manipulate 15 the cross threads of a run in the usual manner for closing the run and repairing the stocking or other fabric. When the lower resilient portion of the guiding sleeve is gripped by the operator and the tubular yield- 20 ably mounted section of the plunger is held, the plunger may continue reciprocating, and the upper and lower springs will be automatically compressed and will alternately expand to move upwardly and downwardly 25 on the tubular member 110. While the split in the sleeve is shown at an interval of ninety degrees, it will be understood that such interval may be varied. The knurling of the sleeve provides a better grip by which the operator 30 can hold and push the hollow head back and forth in re-looping the threads of the run to be repaired. As the occasion requires the operator may wish to stop the action of the 35 needle momentarily, and by a slight pressure on the split outer guiding tube may cause the same to grip the yieldably actuated tubular member of the positively driven plunger at its vertical motion either upward or downward, and thus restrain it in its action. How- 40 ever, as long as the motive power has not stopped, the collapsible shaft will continue to rotate the eccentric head formed by the fork and thus actuate the positively driven plunger, but on arresting the plunger sleeve or tu- 45 bular member 110 the plunger head will compress the upper and lower springs either in its upward or downward stroke. This will enable the operator to hold the needle inactive as long as desired, and immediately upon 50 release of the pressure against the resilient split portion of the guiding sleeve, the plunger sleeve will resume its reciprocation. Various types of needles may be employed, and the stroke of the plunger may be varied by 55 introducing a screw driver through the opening 99 and rotating the adjusting screw to adapt the stroke to the particular type of needle employed. When the adjusting screw is rotated, the sliding block will be caused to 60 move either closer to the axis of the collapsible 65

shaft, or further away from the axis, thereby changing the distance between the wrist pin and the axis and varying the length of the stroke of the eccentric driving mechanism. Also, the position of the needle with respect 70 to the slot of the hollow form may be varied by loosening the screw 68 and partially rotating the hollow head on the hollow extensible arm and the needle may be changed from a vertical position to an inclined position at either side of the vertical, to arrange the needle to reciprocate vertically through the material or to enter the fabric at an angle, and the hollow arm is adapted to be adjusted laterally to arrange the slot in proper position to cooperate with the changed position 75 of the needle. Also, when a run is more than the width of a single thread the hollow form may be adjusted laterally to enable the needle after repairing or re-knitting one run to operate on a second or a third run without the necessity of changing the position of the material on the hollow form.

When it is desired to change the position of the needle to arrange the hook and the latch so as to extend either forward or backward to make a repair either from the hem towards the toe or from the toe towards the hem of a stocking, the section 131 of the clutch is partially rotated, and when force is applied to rotate the said section 131 of the clutch the oppositely beveled or transversely tapered rib 135 will slide on the oppositely inclined walls of the groove 134 and will force the clutch section 131 downwardly, compressing the spring 127 and disengaging the rib 135 from the groove 134. Upon completion of the rotation of the section 131 one hundred and eighty degrees, the rib 135 will again be brought into alignment with the groove 134 and the compressed spring 127 will cause the rib 135 to snap into the groove 134. When the rib 135 is re-engaged with the groove 134 the spring will maintain the parts in such interlocked relation and there will be no liability of the needle accidentally leaving such position or adjustment.

The knitted fabric to be repaired is arranged on the form with the cross threads of the run to be repaired substantially uniformly spaced from one another, and the needle automatically loops successively the spaced threads of the run through loops formed in the preceding threads in the usual well known manner, similar to repairing such runs by hand. In repairing the run the needle is moved manually by the operator along the run to feed the needle to the fabric, while the fabric remains supported on the form in a stationary position with respect to the manually fed needle.

While in the specific embodiment of the invention illustrated in the accompanying drawings the machine is designed particularly for mending the runs in stockings, yet it

will be readily understood that the invention is not limited to the repair of stockings but is applicable to the repair of runs in various kinds of knitted fabrics where the run may be closed by looping the cross threads of the run through loops formed in the preceding threads.

What is claimed is:

1. A method of repairing runs in knitted fabrics which consists in spacing the threads which extend transversely of the run to be repaired substantially uniformly from one another, automatically looping successively the spaced threads through loops formed in the preceding threads, and manually moving the looping means along the run to thereby feed the looping means at the will of the operator by hand to the successive cross threads of the said run.

2. A method of repairing runs in knitted fabrics consisting in supporting the fabric and holding the ladder-like threads of a run spaced substantially uniformly from one another, reciprocating a needle through the run to manipulate the threads thereof automatically to close the run, and manually moving the needle along the run to thereby feed the needle at the will of the operator by hand to the successive threads of the run.

3. A method of repairing runs in knitted fabrics consisting in supporting a relatively large portion of the fabric on the form, mechanically reciprocating a needle through a run in a fabric to manipulate the threads thereof to close the run, and manually moving the needle along the run to feed the needle at the will of the operator by hand to the successive cross threads of the run without changing the position of the fabric on the form.

4. In a machine for repairing runs in knitted fabrics, means for forming a loop in each fabric thread which crosses the run to be repaired, means to automatically draw each successive loop through the loop formed in the preceding cross thread, means for firmly holding the fabric during the looping operations, and means for manually moving the looping means along the run to feed the said means by hand to the successive cross threads.

5. In a machine for repairing runs in knitted fabrics, means for forming a loop in each fabric thread which crosses the run to be repaired, means automatically to draw each successive loop through the loop formed in the preceding cross thread, means for firmly holding the fabric during the looping operations, means for manually moving the looping means along the run to feed the said means by hand to the successive cross threads, and a relatively long support for the fabric to enable the entire run to be repaired without changing the position of the fabric on the support.

6. A machine for repairing runs in knitted

fabrics including a needle, mechanical means for operating the needle to manipulate the threads of a run automatically to close the run, and movable means for carrying the needle so that said means and the needle may be moved at the will of the operator along the run to the successive threads of a run.

7. A machine for mending runs in fabrics including a needle, mechanical means for actuating the needle to manipulate the threads of a run automatically to close the run, means for supporting the fabric in position to be operated on by the needle, and means for carrying the needle so that said means and the needle may be moved at the will of the operator along the run to the successive cross threads of the run.

8. A machine for mending runs in fabrics, including a form for supporting a fabric in a stationary position, a mechanically actuated needle for manipulating the threads of a run automatically for closing the run, and means for carrying the needle so that said means and the needle may be moved at the will of the operator along the run to the successive cross threads of the run.

9. A machine for mending runs in fabrics, including a form consisting of a projecting arm arranged to receive the stocking to be repaired, means for holding the stocking on the form, a needle, mechanically operable means for actuating the needle to manipulate the threads of a run automatically to close the run, and manually movable means for carrying the needle along the run whereby to feed the needle by hand at the will of the operator to the successive cross threads of the run.

10. A machine for mending runs in fabrics including a form arranged to extend into a stocking for supporting the same, means for clamping the stocking on the form, a needle, mechanical means for actuating the needle to manipulate the threads of a run automatically to close the run, and means for supporting and carrying the needle so that said supporting and carrying means and the needle may be moved by hand at the will of the operator along the run to the successive cross threads of the run.

11. A machine for mending runs in fabrics including a form arranged to extend into a stocking for supporting the same, a needle, mechanical means for actuating the needle to manipulate the threads of a run automatically to close the same, spaced clamping means for holding the stocking on the form with the cross threads of the run substantially uniformly spaced, and means for moving the needle over the run longitudinally of the latter at the will of the operator.

12. A machine for mending runs in fabrics including a form arranged to extend into a stocking for supporting the same, a needle, mechanical means for actuating the needle to

- manipulate the threads of a run automatically to close the said run, and a plurality of clips embracing the form and clamping the stocking thereon, said clips being adjustable along the form to enable them to be arranged clear of the needle.
18. A machine for mending runs in fabrics including a needle, means for operating the needle to automatically manipulate the threads of a run to close the latter, a laterally adjustable form arranged to support the fabric to be repaired in position to be operated on by the needle, means for guiding the form in its lateral adjustment, a nut carried by the form, and a transversely disposed shaft provided with threads engaging the said nut for moving the same laterally when the shaft is rotated.
19. A machine for mending runs in fabrics including a needle, means for operating the needle to automatically manipulate the threads of a run to close the latter, a laterally adjustable form arranged to support the fabric to be repaired in position to be operated on by the needle, means for guiding the form in its lateral adjustment, a nut carried by the form, a transversely disposed shaft provided with threads engaging the said nut for moving the same laterally when the shaft is rotated, an operating lever connected with the shaft, and automatically operable means connected with the operating lever for locking and releasing the same.
20. A machine for mending runs in fabrics including a frame provided with spaced transversely disposed guiding surfaces, a needle, means for operating the needle to automatically manipulate the threads of a run in a fabric to close the run, a form arranged to support the fabric in position to be operated on by the needle, said form being mounted between the guiding surfaces for lateral adjustment, and means for moving the form laterally and for securing the form in its adjustment.
21. A machine for mending runs in fabrics including a frame provided with a transverse guide, a form mounted in the guide, means for adjusting the form laterally in the said guide, means for clamping a fabric on the form, said clamping means being carried by the form in its lateral adjustment, a needle, and means for operating the needle to automatically manipulate the threads of a run in the fabric to close the run.
22. A machine for mending runs in fabrics including a frame, a needle, means for operating the needle to automatically manipulate the threads of a run in the fabric to close the run, a form mounted on the frame and arranged to support the fabric in position to be operated on by the needle, means for adjusting the form laterally with respect to the needle to enable runs of different widths to be repaired, and a plurality of clamping devices mounted on the form at spaced points for holding the fabric in position, said clamping means being carried by the form in its lateral adjustment.
23. A machine for mending runs in fabrics including a frame, a needle, means for oper-

- ating the needle to automatically manipulate the threads of a run in the fabric to close the run, a form mounted on the frame and arranged to support the fabric in position 5 to be operated on by the needle, means for adjusting the form laterally with respect to the needle to enable runs of different widths to be repaired, a clamping lever mounted on the form and having a jaw arranged to engage the fabric, and yieldable means mounted on the frame and connected with the lever for maintaining the said jaw in engagement with the fabric under a predetermined pressure without interfering with the lateral adjustment of the form. 10 24. A machine for mending runs in fabrics including a frame, a needle, means for operating the needle to automatically manipulate the threads of a run in the fabric to close the run, a form mounted on the frame and arranged to support the fabric in position to be operated on by the needle, means for adjusting the form laterally with respect to the needle to enable runs of different widths to be repaired, a clamping lever mounted on the form and having a jaw arranged to engage the fabric, yieldable means mounted on the frame and connected with the lever for maintaining the said jaw in engagement with the fabric under a predetermined pressure without interfering with the lateral adjustment of the form, and operating means connected with the clamping lever for releasing the fabric. 20 25 30 35 40 45 50 55 60 65 70 75 80 85 90 95 100 105 110 115 120 125 130
26. A machine for mending runs in fabrics including a frame, a needle, means for operating the needle to automatically manipulate the threads of a run in the fabric to close the run, a form mounted on the frame and arranged to support the fabric in position to be operated on by the needle, means for adjusting the form laterally with respect to the needle to enable runs of different widths to be repaired, a transverse shaft mounted on and carried by the form, a clamping arm rigid with the shaft and provided with a jaw arranged to engage the fabric for securing the same on the form, an operating arm also rigid with the said shaft, a spring connected with the operating arm and with the frame for maintaining the clamping arm in engagement with the fabric, and operating means connected with the operating arm for releasing the fabric, said spring and operating means permitting lateral movement of the form in the adjustment thereof. 26. A machine for mending runs in fabrics including a frame, a needle, means for operating the needle to automatically manipulate the threads of a run in the fabric to close the run, a form mounted on the frame and arranged to support the fabric in position to be operated on by the needle, means for adjusting the form laterally with respect to the needle to enable runs of different widths to be repaired, a plurality of spaced clips embracing the form intermediate the ends thereof for securing the fabric on the form, said clips being adjustable along the form to enable them to be arranged clear of the needle, and a clamping lever mounted on the form at the rear end thereof and arranged to engage the fabric. 27. A machine for mending runs in fabrics including a frame, a form mounted on the frame and arranged to support the fabric to be repaired and provided at the top with a non-metallic plate arranged to receive the fabric adjacent to a run, a clamping lever mounted on the form and provided with a yieldable fabric engaging surface arranged to clamp the fabric against the said non-metallic plate, a plurality of clamping devices arranged to clamp the fabric against the form at points spaced from the said lever, a needle, and means for operating the needle to automatically manipulate the threads of a run in the fabric to close the run. 28. A machine for mending runs in fabrics including a frame having an opening and provided at the top and bottom thereof with horizontal transversely disposed guiding and supporting surfaces, a form arranged to support the fabric to be repaired and having one end mounted in the opening of the frame and guided and supported by the said surfaces, a bracket secured to the form at the bottom thereof at the said opening in the frame and having a nut, a shaft mounted on the frame and having a threaded portion engaging the nut for shifting the form laterally, a needle, and means for operating the needle to automatically manipulate the threads of a run in the fabric to close the run. 29. A machine for mending runs in fabrics including a frame, a hollow form mounted on the frame and projecting therefrom and adapted to support a fabric in position to be repaired, said form being provided with a needle receiving slot, a needle, means for operating the needle to automatically manipulate the threads of a run in the fabric to close the run, illuminating means arranged interiorly of the machine and adapted to project rays of light through the slot in the form upon the threads of the run, and means for shielding the operator from the direct rays of light from the illuminating means. 30. A machine for mending runs in fabrics including a frame, a hollow form mounted on the frame and projecting therefrom and adapted to support a fabric in position to be repaired, said form being provided with a needle receiving slot, a needle, means for operating the needle to automatically manipulate the threads of a run in the fabric to close the run, a lamp arranged inter-

riorly of the machine for illuminating the threads of the run, a reflector arranged in rear of the lamp for directing rays of light towards the slot in the form, and a combined shield and reflector arranged in front of the lamp and interposed between the same and the slot to shield the lamp from the direct vision of the operator.

31. A machine for mending runs in fabrics including a frame, a hollow form mounted on and projecting from the frame and provided with a longitudinal needle slot and adapted to support the fabric to be repaired, said form being open at the inner end, a lamp 10 mounted within the frame adjacent the open end of the form, a main reflector located in rear of the lamp and directing rays of light towards the interior of the form, and a combined reflector and shield located in front of the lamp and adapted to project rays of light against the main reflector and interposed between the lamp and the slot to prevent the lamp from showing in the direct line of vision of the operator, and a needle 20 for manipulating the threads of a run to close the same.

32. A machine for mending runs in fabrics including means for supporting a fabric in position to be repaired, a needle, means for 30 operating the needle to automatically manipulate the threads of a fabric to close the run, and means for adjusting the needle laterally of the form to arrange the needle either in a perpendicular position or in an 40 inclined position.

33. A machine for mending runs in fabrics including means for supporting a fabric in position to be repaired, a needle, means for operating the needle to automatically manipulate the threads of a fabric to close the run, means for adjusting the needle laterally of the form to arrange the needle either in a perpendicular position or in an inclined 45 position, and means for adjusting the supporting means laterally.

34. A machine for mending runs in fabrics including a form arranged to support the fabric to be repaired and provided with a needle receiving slot, a needle, means for operating the needle to automatically manipulate the threads of a run in the fabric to close the run, means for adjusting the needle laterally to arrange the needle either in a perpendicular position or in an inclined position at either side of said perpendicular position, and means for adjusting the form laterally to shift the position of the slot when the needle is adjusted.

35. A machine for mending runs in fabrics comprising a main frame, a form carried by the main frame and arranged to support the fabric to be repaired, a needle, means for operating the needle to manipulate the threads of a run in the fabric to close the run, said means including an extensible and

collapsible driving shaft, and an extensible and collapsible arm mounted on the frame and housing the said driving shaft and carrying the needle operating means and permitting the needle to be manually moved along 70 the form to feed the needle by hand to the successive cross threads of the run.

36. A machine for mending runs in fabrics comprising a main frame provided with means for supporting the fabric in position 75 to be repaired, a needle, means for operating the needle to automatically manipulate the threads of a run in the fabric to repair the same, said operating means including an extensible and collapsible driving shaft, and an extensible and collapsible hollow horizontal arm housing the operating shaft and carrying the needle operating mechanism and adapted to permit the needle to be manually moved over the fabric supporting means for 85 feeding the needle by hand to the successive cross threads of a run.

37. A machine for mending runs in fabrics comprising a main frame provided with means for supporting the fabric to be repaired, a hollow extensible and collapsible arm mounted on the frame and composed of a plurality of telescoping sections, a needle, and means for operating the needle to automatically manipulate the threads of a run in 95 the fabric to close the run, said needle operating means being carried by the extensible and collapsible arm and including an extensible and collapsible shaft having telescoping sections housed within the hollow arm, 100 said telescoping sections of the arm and the driving shaft permitting the needle to be manually moved over the support for feeding the needle by hand to the successive threads of the run in the fabric.

38. A machine for mending runs in fabrics comprising a main frame provided with means for supporting the fabric to be repaired, a needle, means for operating the needle to manipulate the threads of a run in 110 a fabric to close the run, and manually operable means for permitting the needle to be moved over the support to feed the needle by hand to the successive threads of the run, including an extensible and collapsible arm 115 mounted on and projecting from the main frame and having a plurality of telescoping sections.

39. A machine for mending runs in fabrics comprising a main frame, means for supporting the fabric to be repaired, a needle, and means for operating the needle to automatically manipulate the threads of a run in the fabric to close the run, including an extensible and collapsible driving shaft having a plurality of telescoping sections and adapted to permit the needle to be manually moved over the support for feeding the needle by hand to the successive threads in the run.

40. A machine for repairing runs in fabrics 130

comprising a main frame provided at the top with a tubular bearing portion, a hollow arm extending from the top of the frame and composed of a plurality of telescoping sections, said sections telescoping into one another and into said tubular portion of the frame, a head carried by the hollow arm, a driving shaft housed within the hollow arm and composed of telescoping sections and extending to the said head, a needle carried by the head, means also carried by the head and connected with and actuated by the driving shaft for reciprocating the needle and manipulating the threads in a run in the fabric to close the run, and means for supporting the fabric in position to be operated on by the needle, the latter being manually movable over the supporting means to permit the needle to be fed by hand to the successive threads of a run to close the latter.

41. A machine for mending runs in fabrics comprising a main frame, a hollow expandable and collapsible arm mounted on and extending from the frame and composed of a plurality of telescoping sections provided with longitudinal slots, means carried by the sections and operating in the slots for limiting the longitudinal movement of the sections and for holding the sections against rotary movement, a hollow head mounted on the said arm, a needle carried by the head, and means carried by the head and the arm for reciprocating the needle to manipulate the threads of a run in the fabric to close the run.

42. A machine for mending runs in fabrics comprising a main frame, a hollow expandable and collapsible arm mounted on and extending from the frame and composed of a plurality of telescoping sections provided with longitudinal slots, means carried by the sections and operating in the slots for limiting the longitudinal movement of the sections and for holding the sections against rotary movement, a hollow head mounted on the said arm, a needle carried by the head, and means carried by the head and the arm for reciprocating the needle to manipulate the threads of a run in the fabric to close the run, said needle reciprocating means including a collapsible and extensible shaft having a plurality of telescoping sections provided with longitudinal slots and having means operating in the slots to limit longitudinal sliding movement of the sections and to prevent relative rotary movement of the same.

43. A machine for mending runs in fabrics comprising a main frame, an arm extending from the main frame, a head mounted for rotary movement on the arm, a needle carried by the head in the rotary movement thereof whereby the needle is adapted to be adjusted laterally to arrange the needle either in a perpendicular position or in an inclined position, and means for reciprocating the needle to automatically manipulate the

threads of the run in the fabric to close the same.

44. A machine for mending runs in fabrics including a main frame, a hollow arm extending from the main frame, a hollow head mounted for rotary movement on the arm and provided with an arcuate slot and having means operating in the slot for securing the head in rotary adjustment, a needle carried by the head in the rotary adjustment thereof and adapted to be arranged either in a perpendicular position or in an inclined position, and means for operating the needle to automatically manipulate the threads of a run in the fabric to close the run.

45. A machine for mending runs in fabrics comprising a main frame, a collapsible and extensible supporting arm extending from the main frame and composed of a plurality of telescoping sections and provided at its outer end with a head, an extensible and collapsible driving shaft composed of a plurality of telescoping sections and housed within the supporting arm and extending through the frame to the rear side thereof, means connected with the rear end of the driving shaft for rotating the latter, a needle carried by the said head, and eccentric means located within the head and connected with and actuated by the driving shaft for reciprocating the needle for automatically manipulating the threads of a run in the fabric to close the run.

46. A machine for mending runs in fabrics comprising a main frame, a collapsible and extensible supporting arm extending from the main frame and composed of a plurality of telescoping sections and provided at its outer end with a head, an extensible and collapsible driving shaft composed of a plurality of telescoping sections and housed within the supporting arm and extending through the frame to the rear side thereof, means connected with the rear end of the driving shaft for rotating the latter, a needle carried by the said head, eccentric means located within the head and connected with and actuated by the driving shaft for reciprocating the needle for automatically manipulating the threads of a run in the fabric to close the run, and means for enabling the stroke of the needle to be adjusted and changed from the exterior of the head without removing or changing the parts of the said eccentric means.

47. A machine for mending runs in fabrics comprising a main frame, a supporting arm extending from the main frame and provided at its outer end with a head, a needle carried by the head, a driving shaft extending through the arm to the head, an eccentric drive for reciprocating the needle to automatically manipulate the threads of a run in the fabric to close the run, and means for enabling the stroke to be adjusted and varied

in length from the exterior of the head without removing and changing the parts of the eccentric drive.

48. A machine for mending runs in knitted fabrics including an eccentric drive, a needle, and means for yieldably connecting the needle with the eccentric drive adapted to permit the needle to be stopped without interrupting continuous operation of the eccentric drive.

49. A machine for mending runs in knitted fabrics including an eccentric drive, a needle, means for yieldably connecting the needle with the eccentric drive comprising a plunger actuated by the eccentric drive, a member slidably connected with the plunger and carrying the needle, and cushioning means connected with the member and the plunger for yieldably holding the said member normally against relative movement and adapted to permit the member and the needle to be stopped without interfering with the continuous operation of the plunger.

50. A machine for mending runs in knitted fabrics including an eccentric drive, a needle, and means for yieldably connecting the needle with the eccentric drive comprising a plunger directly actuated by the eccentric drive and provided with a head, a sleeve arranged on the plunger and receiving the head and carrying the needle, and cushioning springs arranged within the sleeve at opposite sides of the head and interposed between the sleeve and the plunger for yieldably holding the sleeve normally against relative movement.

51. A machine for mending runs in knitted fabrics including a positive drive, a reciprocating needle, and means for yieldably connecting the reciprocating needle with the positive drive comprising a reciprocating plunger actuated by the drive, a member slidably connected with the plunger and carrying the needle, cushioning means for holding the member against relative movement on the plunger, and manually operable means for holding the member to arrest the operation of the needle without interfering with continuous operation of the plunger and the drive.

52. A machine for mending runs in knitted fabrics including a positive drive, a reciprocating needle, means for yieldably connecting the reciprocating needle with the positive drive comprising a plunger actuated by the drive, a sleeve slidably mounted on the plunger and carried by the same, and cushioning means interposed between the sleeve and the plunger, and a guiding sleeve slidably receiving the said sleeve and having manually operable portions adapted to engage and hold the first mentioned sleeve to arrest the needle without interfering with continuous operation of the positive drive and plunger.

53. A machine for mending runs in knitted fabrics including a positive drive, a reciprocating needle, means for yieldably connecting the reciprocating needle with the positive drive comprising a plunger actuated by the drive, a sleeve slidably mounted on the plunger and carried by the same, and cushioning means interposed between the sleeve and the plunger, and a guiding sleeve slidably receiving the sleeve and having a split portion adapted to be compressed by the operator for frictionally engaging the first mentioned sleeve to arrest the needle without interfering with continuous operation of the drive and plunger.

54. A machine for mending runs in knitted fabrics including a means for supporting a fabric in position to be repaired, means for reciprocating a needle through the fabric for manipulating the threads of a run to close the latter, said needle being movable over the support, and means for permitting the needle to be reversed to enable the repair to be started from either end of a run.

55. A machine for repairing runs in knitted fabrics including a drive, needle carrying means actuated by the drive for reciprocating the needle, said means comprising clutch members having coacting interlocking faces and pivotally connected to permit reversal of the needle.

56. A machine for repairing runs in knitted fabrics comprising a needle drive, reciprocating means actuated by the drive and comprising clutch members having coacting interlocking faces, one of the clutch members being provided with needle clamping means and pivotally mounted for axial movement on the other clutch member to permit reversal of the needle.

57. A machine for repairing runs in knitted fabrics including an eccentric drive, reciprocating means actuated by the drive and provided with needle carrying means comprising clutch sections having coacting interlocking faces, one of the clutch sections having needle clamping means and pivotally connected with the other clutch section for axial rotation to reverse the needle, and means for yieldably holding the coacting interlocking faces of the clutch sections in engagement with each other.

58. A machine for repairing runs in knitted fabrics including a needle drive, a reciprocating member actuated by the drive and provided with needle carrying means comprising a relatively fixed clutch section carried by the reciprocating member, a relatively movable clutch section having needle clamping means, a longitudinal pivot connecting the needle carrying section with the relatively fixed section to permit axial rotation for reversing the needle, and a coiled spring disposed on the pivot for holding the

- clutch sections normally in engagement with each other.
59. A machine for repairing runs in knitted fabrics including a needle drive, a reciprocating member actuated by the drive and provided with needle carrying means comprising a relatively fixed clutch section mounted on the said member, a rotary clutch section having needle clamping means, one of the sections being provided with approximately V-shaped groove and the other section having a substantially V-shaped rib fitting in the groove, and means for yieldably maintaining the rib normally in engagement with the groove. 70
60. A machine for repairing runs in knitted fabrics including a needle drive, a reciprocating plunger actuated by the needle drive, a sleeve slidably mounted on the plunger and having cushioning means interposed between the sleeve and the plunger, said sleeve being provided with needle carrying means comprising a clutch section secured in one end of the sleeve and provided with a socket, a rotary clutch section having needle clamping means, a longitudinal pivot secured to the rotary clutch section and extending through the fixed clutch section and having a head arranged in the clutch thereof, and cushioning means mounted in the socket and operating against the head to maintain the clutch sections normally in engagement with each other. 80
61. A machine for repairing runs in knitted fabrics including a reciprocating needle, an eccentric drive comprising a shaft having spaced transversely aligned lugs, a screw mounted in the said lugs, a slidable block engaged by the screw and having a wrist pin adapted to be adjusted by the screw to vary the length of the stroke of the eccentric drive, and means for connecting the needle with the wrist pin. 90
62. A machine for repairing runs in knitted fabrics including a reciprocating needle, an eccentric drive comprising a shaft having spaced transversely aligned lugs, a screw mounted in the said lugs, a slidable block engaged by the screw and having a wrist pin adapted to be adjusted by the screw to carry the length of the stroke of the eccentric drive, a reciprocating plunger carrying the needle, and a pitman pivotally connected with the plunger and mounted on the wrist pin. 100
63. A machine for repairing runs in knitted fabrics including a hollow head, an eccentric drive arranged within the hollow head and comprising a driving shaft having spaced transversely aligned lugs, a transversely disposed adjusting screw mounted in the lugs, a slidable block operated between the lugs and engaged by the adjusting screw to vary the stroke of the eccentric drive, a pitman pivotally connected with the slidable block and adapted to actuate a needle, said hollow 110
- head being provided with an opening arranged in the plane of the adjusting screw and adapted to permit an instrument to be introduced into the head for adjusting the screw to vary the length of the stroke without the substitution of parts. 120
64. A method of repairing runs in knitted fabrics which consists in spacing the threads which extends transversely of the run to be repaired substantially uniformly from one another, a needle for automatically looping successively the spaced threads through loops formed in the preceding threads, and manually moving the needle while perpendicular or at an angle along the run and thereby feed the needle by hand to the successive cross threads of the run. 130
65. In a machine for repairing runs in knitted fabrics, means for forming a loop in each fabric thread which crosses the run to be repaired, means to draw each successive loop through the loop formed in the preceding cross thread, means for firmly holding the fabric during the looping operations, and means whereby to manually move the looping means at different times along different runs and thereby feed the said means by hand to the successive cross threads of the respective runs. 140
66. A machine for mending runs in fabrics including a form for supporting a fabric in a stationary position, a needle for manipulating the threads of a run for closing the run, and manually operable, collapsible means for the support of the needle and for carrying the needle along the run whereby to feed the needle by hand to the successive cross threads of the run. 150
67. A machine for mending runs in fabrics including a frame, a form mounted on the frame and arranged to support the fabric to be repaired and provided at the top with a non-metallic plate arranged to receive the fabric adjacent to a run, and clamping means mounted on the form and provided with a yieldable fabric engaging surface arranged to clamp the fabric against said non-metallic plate, a needle, and means for operating the needle to manipulate the threads of a run in the fabric to close the run. 160
68. A machine for mending runs in fabrics comprising a frame provided with means for supporting the fabric to be repaired, a needle, means for operating the needle to manipulate the threads of a run in a fabric to close the run, and manually operable, collapsible and extensible means for permitting the needle to be moved over the support and thereby feed the needle by hand to the successive threads of the run. 170
69. A device of the character described comprising a relatively long hollow form for the reception of a stocking and the support of a relatively long stretch of the stocking to be mended and provided with a relatively 180

long narrow longitudinally disposed slot for the passage of a needle operable through the fabric of a stocking and projection into said slot, and means embracing the form and yieldably engaging the sides thereof for clamping the stocking on the form.

70. A device of the character described comprising a relatively long hollow form for the reception of a stocking and the support **10** of a relatively long stretch of the stocking to be mended and provided with a relatively long narrow longitudinally disposed slot for the passage of a needle operable through the fabric of a stocking and projection into said **15** slot, and a plurality of clips embracing the form and clamping the stocking thereon.

71. A device of the character described comprising a relatively long hollow form for the reception of a stocking and the support **20** of a relatively long stretch of the stocking to be mended and provided with a relatively long narrow longitudinally disposed slot for the passage of a needle operable through the fabric of a stocking and projection into said **25** slot, and a plurality of clips embracing the form and clamping the stocking thereon, said clips being adjustable along the form to enable them to be arranged clear of said slot.

72. A machine for mending runs in fabrics **30** including a frame, a needle, means for operating the needle to automatically manipulate the threads of a run in the fabric to close the run, a form mounted on the frame to support the fabric in position to be operated on **35** by the needle, and means for adjusting the form with respect to the needle to enable runs of different widths to be repaired.

73. A machine for mending runs in knitted fabrics including means for supporting **40** a relatively large portion of a stocking on a relatively long supporting form in position to be repaired, a needle, means for operating the needle through the fabric for manipulating the threads of a run to close the latter, **45** one of said means being movable relative to the other, and means for permitting the needle to be reversed to enable the repair to be started from either end of a run, the needle being manually movable at will by hand in **50** a definite plane in opposite directions along the form to close the run.

74. In a machine for repairing runs in a knitted fabric, means for supporting the fabric having a plurality of runs on a supporting means, a needle, means to reciprocate the needle, means whereby to adjust the needle to different positions for definite movement through different runs, and means to adjust the supporting means laterally so as **60** to position the respective runs with relation to the operating portion of the needle for closing of different runs in the same piece of fabric without changing the position of the fabric on the form, the needle being movable **65** at will by hand over the form to the successive

threads of the respective runs to effect such closing of the runs.

75. A method of repairing runs in knitted fabrics which consists in disposing a fabric having a plurality of runs on a supporting form, mechanically reciprocating a needle through the separate runs, one run at a time, for automatically looping successively the spaced threads of a run through loops formed in the preceding threads of such run and **75** with the needle operating in a definite plane through the respective run, moving one of the said parts at will by hand to present the needle to the successive cross threads of the respective runs to close the same and without changing the position of the fabric on the form.

In testimony whereof I have hereunto set my hand, this 11th day of June, 1929.

JOSEPH S. PECKER.
